MEANS FOR ATTACHING HEELS TO SHOES

David E. Cool, St. Louis, Mo.

Application February 4, 1933, Serial No. 655,153

4 Claims. (Cl. 36—34)

This invention relates generally to shoes and more specifically to an improved method and improved means for attaching French and other types of high heels formed of wood to women's shoes, the predominant object of the invention being to provide an improved method and improved means for attaching high wood heels to shoes whereby said heels are more securely held in place than was the case with high heels secured to shoes in accordance with the practices heretofore followed.

Prior to this invention considerable trouble and annoyance was caused by high heels of women's shoes being pulled loose from the shoes during use thereof. This was particularly true of wood heels which, because of the danger of splitting said wood heels when same were being applied to the shoes, had to be applied to the shoes in accordance with methods which did not always afford the desired security of attachment. The main purpose of the present invention is to provide an improved method and improved means for attaching wood heels to women's shoes in a very secure manner, and this secure attachment of the heels is attained without danger of splitting the heels when same are applied to the shoes.

Figure 1 is a fragmentary view partly in side elevation and partly in section of a woman's shoe and illustrating the heel of said shoe attached to the shoe in accordance with this invention.

Figure 2 is a cross-section taken on line 2—2 of Figure 1.

Figure 3 is a fragmentary sectional view showing the improved heel attaching means as same appears prior to final attachment of the heel.

Figure 4 is a view similar to Figure 3 but illustrating the heel attaching means after final attachment of the heel has taken place.

In the drawing, wherein is shown for the purpose of illustration merely, one embodiment of the invention, A designates a woman's shoe of ordinary construction, said shoe A being provided with a high heel B formed of wood or like material. The shoe A is provided with the usual outsole C, insole D, upper E, counter F, and lining G, but as these shoe parts have no reference to the present invention they are illustrated and referred to herein solely so that a clear understanding of the invention may be had.

Formed through the insole and outsole of the shoe A and extended downwardly into the heel B thereof is a hole I which may be produced by drilling or otherwise. The hole I terminates

in a closed lower end which is located some distance below the top face of the heel B. Arranged in the hole I is an elongated sleeve 2 which is provided at its upper end with an annular, outstanding flange 3. The sleeve 2 is formed from metal or other suitable material, and preferably the flange 3 constitutes an integral part of said sleeve. As shown clearly in Figures 1, 3 and 4 of the drawing, the flange 3 is disposed with respect to the major axis of the sleeve 2 at an angle other than a right angle so that the top face of said flange may be arranged parallel with relation to the top face of the insole D of the shoe A. Also as shown in the views mentioned the flange 3 is countersunk in the insole so that no protuberance is present at the face of the insole which would cause discomfort to the wearer of the shoe.

Formed at the lower end of the sleeve 2 is a plurality of prongs or teeth-like extensions 4, which preferably constitute integral portions of the sleeve. The sleeve 2 is so formed that each of the prongs or teeth-like extensions is curved inwardly before the sleeve is finally applied to a shoe, as shown most clearly in Figure 3; in other words at its extreme lower end the sleeve 2 is provided with a broken or interrupted, annular depression, the interruptions of which occur between the prongs or teeth-like extensions 4. The curvatures of the prongs or teeth-like extensions are designated in Figure 3 by the reference character 5.

In applying heels to shoes in accordance with this invention the heels are temporarily attached to the shoes and the holes I are produced by drilling or otherwise, said holes, as already explained herein, being formed through the insoles and outsoles and being extended into the heels of the shoes. The sleeves 2 are then arranged in the holes so that the flanges 3 thereof are properly seated with respect to the insoles. The final step of actually attaching a heel to a shoe in accordance with the invention is accomplished by introducing a suitable tool T into the sleeve and forcibly moving same downwardly through said sleeve. When the downwardly moving tool T contacts with the curved inner faces of the prongs 4, said prongs are cammed outwardly with the result that the sharp ends of said prongs are forced into the wood heel at the face of the opening I as shown in Figures 1 and 4. In this manner, the sleeve 2 is securely attached to the heel, and because the sleeve at its upper end is firmly connected to the insole and outsole of the shoe a very

secure attachment of the heel to the shoe proper is obtained. The tool T may be operated in any suitable manner when a heel is being attached to a shoe in accordance with this invention; that 5 is to say said tool may be manually operated, or, it may be a part of a suitable machine which may be employed in attaching the heels to the shoes. Preferably, however, I desire the tool T to be provided with a shoulder T' which will 10 contact with the flanges of the sleeves 2 so as to limit downward movement of the tool with respect to the sleeves.

I claim:

- 15 1. A device for attaching a heel to a shoe comprising a hollow element which is arranged in alined openings formed in the sole portion and the heel of the shoe, a flange at one end of said hollow element adapted to engage the sole portion of the shoe, said flange being countersunk 20 in the sole portion of the shoe so that the top face of the flange is substantially flush with the top face of the sole portion of the shoe, and displaceable portions adapted to be forced outwardly so as to be embedded in the material of 25 the heel, said displaceable portions being provided with curved faces adapted to receive in contact therewith a tool which is moved through said hollow element for the purpose of moving said displaceable portions outwardly.
- 30 2. A device for attaching a heel to a shoe comprising a hollow element which is arranged in alined openings formed in the sole portion and the heel of the shoe, a flange at one end of said hollow element adapted to engage the sole portion of the shoe, said flange being countersunk in the sole portion of the shoe so that the top 35 face of the flange is substantially flush with the top face of the sole portion of the shoe, and displaceable portions in the form of prongs 40 adapted to be forced outwardly so as to be embedded in the material of the heel, said dis-

placeable portions being provided with offset faces adapted to receive in contact therewith a tool which is moved through said hollow element for the purpose of moving said displaceable portions outwardly.

3. A device for attaching a heel to a shoe comprising a hollow element which is arranged in alined openings formed in the sole portion and the heel of the shoe, a flange at one end of said hollow element adapted to engage the sole portion of the shoe, said flange being countersunk in the sole portion of the shoe so that the top face of the flange is substantially flush with the top face of the sole portion of the shoe, and displaceable portions adapted to be forced outwardly so as to be embedded in the material of the heel, said displaceable portions being located at an end of said hollow element and being provided with offset faces adapted to receive in contact therewith a tool which is moved through said hollow element for the purpose of moving said displaceable portions outwardly.

4. A device for attaching a heel to a shoe comprising a hollow element which is arranged in alined openings formed in the sole portion and the heel of the shoe, a flange at one end of said hollow element adapted to engage the sole portion of the shoe, said flange being countersunk in the sole portion of the shoe so that the top face of the flange is substantially flush with the top face of the sole portion of the shoe, and displaceable portions at the opposite end of said hollow element adapted to be forced outwardly so as to be embedded in the material of the heel, said displaceable portions being curved longitudinally of the sleeve and curved faces thereof being adapted to receive in contact therewith a tool which is moved through said hollow element whereby said displaceable portions are moved outwardly.

DAVID E. COOL.
